(57) **CLAIM**

The ornamental design for a turkey fryer support device, as shown and described.

DESCRIPTION

FIG. 1 is a perspective view of a turkey fryer support device;

FIG. 2 is a front view thereof;

FIG. 3 is a back view thereof;

FIG. 4 is a side view thereof;

FIG. 5 is a side view thereof;

FIG. 6 is a top view thereof; and,

FIG. 7 is a bottom view thereof.

The container shown in broken lines in FIG. 1 forms no part of the claimed design.
